UNITED STATES PATENT OFFICE.

HARRY W. KRAG, OF ST. LOUIS, MISSOURI, ASSIGNOR TO AMERICAN SHOE MACHINERY AND TOOL COMPANY, OF ST. LOUIS, MISSOURI, A CORPORATION OF MISSOURI.

SEWING MACHINE.

Application filed November 4, 1922. Serial No. 599,072.

To all whom it may concern:

Be it known that I, HARRY W. KRAG, a citizen of the United States, and a resident of the city of St. Louis and State of Missouri, have invented a new and useful Improvement in Sewing Machines, of which the following is a specification.

This invention relates principally to sewing machines of the type employing a straight needle and a presser-foot. One of the principal objects of the present invention is to produce a simple, economical and efficient guide device for maintaining the line of stitches a uniform distance from the edge of the work. Another object is to provide means for varying the location of the line of stitches with relation to the edge of the work. Another object is to provide means for pressing the work against the work support during the mechanical lift of the presser-foot. Another object is to operatively connect the guide device with the presser-bar, whereby said device is adapted for movement with said presser-bar when the same is manually lifted to insert or remove the work. The invention consists in the combinations and arrangements of parts hereinafter described and claimed.

In the accompanying drawing, wherein like reference numerals indicate like parts wherever they occur,

Fig. 1 is a front elevation of a portion of a sewing machine provided with a guide device embodying my invention;

Fig. 2 is a side elevation of the parts shown in Fig. 1;

Fig. 3 is a plan view of parts located beneath the stitcher-head, the presser bar being shown in horizontal section; and

Fig. 4 is a vertical section on the line 4—4 in Fig. 2.

The sewing machine shown in the accompanying drawing comprises a stitcher-head 5 supporting a vertically reciprocatory presser-bar 6 having a laterally extending presser-foot portion 7 adapted to press the work against a work table 8, which is secured to a shuttle-head 9 containing a rotary shuttle 10. The work supporting plate 8 is provided with a removable plate 11 having an upwardly projecting knife edge 11^a located beneath and in longitudinal alinement with the needle opening in said presser-foot. The knife edge 11^a is adapted

to engage the under surface of the work to 55 cut a stitch receiving channel therein. The hereinbefore described mechanism is well known and it is considered unnecessary to illustrate it in detail.

Mounted in a horizontal bore in a lug 12, which projects upwardly from the rear end of the shuttle-head portion 9 of the sewing machine, is a stud-bolt 13. A hand lever 14 has a cylindrical hub portion 14^a sleeved on the bolt 13. The bolt 13 and 60 hand lever 14 are held in place by a screw 13^a, which is threaded into one end of the bolt, and a nut 13^b which is threaded on the other end thereof. The inner end of the hub portion of the hand lever is provided with 65 a radially extending lug or arm 14^b adapted to support one end of a work guiding or gaging arm 15 which is pivotally secured to said hand lever arm 14^b by means of a horizontal pivot screw 16. The work engaging 70 arm extends forwardly and terminates adjacent to the presser-foot 7 in a laterally extending finger 15^a that overhangs a horizontally disposed rearwardly extending finger 7^a of the presser-foot. 75

Surrounding the bolt 13, between the opposing surfaces of the lug 12 and the hub portion 14^a of the hand lever 14, is a coil spring 17. One end of this spring is brought forward and hooked over the pivotally sup-

ported arm 15; and the opposite end of said spring extends rearwardly of the bolt 13 and bears against the adjacent surface of the frame of the sewing machine. This spring serves to press the free end of the 80 arm down on the work. The hub portion of the hand lever is provided at the outer end with a depending lug 14^c through which

is threaded a screw 18. This screw extends transversely of the hand lever axis and is adapted to bear against the vertical face of a boss 19 that projects horizontally from the frame of the machine. The hub portion of the hand lever is split, as at 20; and a

clamping screw 21 extends through one of the split portions and is threaded into the other, whereby sufficient friction may be developed between the contacting surfaces of the hand lever and its supporting stud to resist rearward movement of the gage arm 100 under pressure of the work, but insufficient to prevent manual operation of said hand lever. 105

The work is shown in the form of an upper layer A and a lower layer B that projects beyond the upper layer. In the present instance, the upper layer A may be considered as representing the welt of a shoe and the lower layer B may be considered as representing the layer that forms the sole of the shoe and is to be attached to the welt before trimming.

- 10 The operation of the device is as follows: After the presser-foot has been manually lifted to permit the work to be properly positioned therebeneath, the presser-foot is lowered to press the work against the work-supporting plate. The hand lever is then manipulated to cause the pivot which supports the gage arm to move transversely of its axis, thereby forcing the free end of the gage arm into engagement with the edge 20 of the welt and the upper surface of the untrimmed sole. The locating screw 18 is then adjusted to cause the end thereof to abut against the boss 19 of the frame of the sewing machine. The screw serves as 25 an adjustable stop for limiting the forward movement of the gage arm. When in the position just described, the forward end of the gage arm serves as a guide or gage for maintaining the line of stitches a uniform 30 distance from the edge of the welt; and, by reason of the downward pressure exerted on the gage arm by the spring 17, said gage arm serves also as a presser-foot to press the work against the work-supporting plate. 35 Thus, a continuous pressure is exerted on the work whereby said work is pressed against the work-supporting plate during the mechanical lift of the presser foot and a stitch receiving channel of uniform depth is obtained.

Sufficient clearance is provided between the rearwardly extending finger 7^a of the presser-foot and the overhanging finger 15^a of the gage arm to prevent the gage arm from being lifted during the mechanical lift of the presser foot. However, when the presser foot is manually lifted to its fullest extent to permit insertion or removal of the work, the finger on the presser-foot engages the finger on the free end of the pivotally supported gage arm and lifts said arm clear of the work.

The invention admits of considerable modification without departing from the invention; therefore, I do not wish to be limited to the exact arrangements shown and described.

What I claim is:

1. A sewing machine comprising a work support provided with a channel cutter, a presser-foot, and a spring-pressed member adapted to engage work comprising an upper layer and a lower layer projecting beyond said upper layer, said spring-pressed member being adapted to guide the work

by contact with the marginal edge of the upper layer thereof and being adapted to press the work against said channel cutter by contact with the upper surface of the lower layer thereof.

70

2. A sewing machine comprising a work support provided with a channel cutter, a presser-foot, a spring-pressed member adapted to engage work comprising an upper layer and a lower layer projecting beyond said upper layer, said spring-pressed member being adapted to guide the work by contact with the marginal edge of the upper layer thereof and being adapted to press the work against said channel cutter by contact with the upper surface of the lower layer thereof, and means for adjusting said member transversely of said presser-foot.

75

3. A sewing machine comprising a work support provided with a channel cutter, a presser-foot, a spring-pressed member adapted to engage work comprising an upper layer and a lower layer projecting beyond said upper layer, said spring-pressed member being adapted to guide the work by contact with the marginal edge of the upper layer thereof and being adapted to press the work against said channel cutter by contact with the upper surface of the lower layer thereof, means for adjusting said member transversely of said presser-foot, and an adjustable stop for limiting the movement of said member towards said presser-foot.

80

4. A sewing machine comprising a work support provided with a channel cutter, a presser-foot, a spring-pressed member adapted to engage work comprising an upper layer and a lower layer projecting beyond said upper layer, said spring-pressed member being adapted to guide the work by contact with the marginal edge of the upper layer thereof and being adapted to press the work against said channel cutter by contact with the upper surface of the lower layer thereof, means for adjusting said member transversely of said presser-foot, an adjustable stop for limiting the movement of said member towards the presser-foot, and means carried by said presser-foot for lifting said member when said presser-foot is manually lifted.

90

5. A sewing machine comprising a work support, a presser-foot, a fixed stud, a hand lever having a hub portion sleeved on said stud and frictionally engaging the same, and a gage arm having one end pivotally supported on the hub portion of said hand lever with its free end in position to engage the work.

110

6. A sewing machine comprising a work support, a presser-foot, a fixed stud, a hand lever having a hub portion sleeved on said stud and frictionally engaging the same, a gage arm having one end pivotally sup-

120

125

130

ported on the hub portion of said hand lever with its free end in position to engage the work, and an adjustable means carried by said hand lever for limiting the 5 movement thereof in one direction.

7. A sewing machine comprising a work support, a presser-foot, a fixed stud, a hand lever having a hub portion sleeved on said stud and frictionally engaging the same, a 10 gage arm having one end pivotally supported on the hub portion of said hand lever with its free end in position to engage the work, a spring for holding the free end of said arm down on the work, adjustable 15 means carried by said hand lever for limiting the movement thereof in the direction of said work, and means carried by the presser-foot for lifting the free end of said arm when the presser-foot is manually lifted.
- 20 8. A sewing machine comprising a work support, a member pivoted to said machine for swinging movement towards and away from said work support, and a work engaging arm having one end supported on said 25 work support in position to engage the work, the other end of said arm being pivotally supported on said pivotally mounted member, said arm being adapted for independent swinging movement in directions

transverse to the pivotal axis of said pivotally mounted member.

9. A sewing machine comprising a work support, an upright arm pivotally supported at its lower end for swinging movement towards and away from said work support, and a work-engaging arm having one end supported on said work support in position to engage the work, the other end of said work gaging arm being pivotally supported on the upper end of said upright 40 arm, said arm being adapted for free swinging movement in directions transverse to the pivotal axis of said upright arm.

10. A sewing machine comprising a work support, an upright arm pivotally supported at its lower end for swinging movement towards and away from said work support, a work gaging arm arranged with one end in position to engage the work, the other end of said work gaging arm being 50 pivotally supported on the upper end of said upright arm, and an adjustable stop movable with said upright arm and adapted to abut against said machine for limiting the movement thereof in one direction. 55

Signed at St. Louis, Missouri, this 1st day of November, 1922.

HARRY W. KRAG.
